UNITED STATES PATENT OFFICE

SAMUEL COHEN, OF BROOKLYN, NEW YORK

RADIOFREQUENCY AMPLIFYING SYSTEM

Application filed October 13, 1925. Serial No. 62,298.

My invention relates broadly to electron tube amplification systems and more particularly to a method for obtaining stability in operation of radio frequency amplifying systems.

One of the objects of my invention is to provide an electron tube amplification system which may be operated over a wide band of frequencies without interference in the several circuits of the amplification system from undesired oscillatory current.

Another object of my invention is to provide a circuit arrangement in an electron tube amplification system in which high resistances are introduced in the electron tube circuits at selected intervals for damping oscillations arising from self-oscillation of the several tubes while not interfering with the normal amplification of the signaling energy.

Still another object of my invention is to provide means in the circuits of the amplifying system for absorbing undesired oscillatory currents and rendering such current ineffective to interfere with signaling currents without damping the signaling energy.

A further object of my invention is to provide a bridge arrangement of resistors for connection with relation to the input and output circuits of each of the electron tubes of a radio frequency amplification system for damping self-oscillatory currents independent of the amplification of the signaling energy over a wide band of frequencies.

My invention will be more fully understood from the following specification by reference to the accompanying drawings, wherein:—

Figure 1 is a diagrammatic view illustrating one embodiment of my invention in an electron tube amplification system; Fig. 2 shows a modified arrangement of the resistors in the several stages of a radio frequency amplifier system; Fig. 3 illustrates an arrangement of resistors in one of the stages of an electron tube amplification system in the form of a balanced bridge; Fig. 4 is a theoretical diagram of the circuit arrangement shown in Fig. 3; and Fig. 5 shows an application of the balanced circuit of Fig. 3 to a

two stage radio frequency amplifying system of a radio receiver.

Referring to the drawings in more detail, reference characters 1, 2 and 3 designate electron tubes each having grid, filament and plate electrodes. The electron tubes 1 and 2 are arranged to function as amplifiers of high frequency radio energy while the electron tube 3 operates as a detector of the radio frequency signaling energy. The receiving apparatus is shown in connection with an antenna system 4 having a primary winding 5 connected therewith with a connection to ground 6. A secondary winding 7 is inductively coupled with the primary winding 5 and the secondary circuit tuned to the frequency of the signal desired to be received by means of variable tuning condenser 8. The output circuit of electron tube 1 includes the primary winding 9 of the radio frequency coupling transformer 10, secondary winding 11 of which is tuned by means of variable condenser 12. The output circuit of the second stage of radio frequency amplification formed by electron tube 2 is connected with a primary winding 14 of the radio frequency coupling transformer 15 having a secondary winding 16 tuned by means of variable condenser 17. The tube 3 includes a grid condenser 18, and grid leak 19 in the grid circuit thereof. The amplification system operates over a wide band of frequencies where the transformers 10 and 15 are electromagnetically coupled and the periodicity of the circuits adjusted by means of variable condensers 8, 12 and 17, and by properly apportioning the inductance of the circuits of the coupling transformers. The cathodes for each of the tubes are supplied with energy from battery A, rheostats 20 and 21 being included in the circuit for regulating the incandescence of the filaments of the tubes 1 and 2 of the amplifying system and rheostat 21 being arranged to control the incandescence of the filament of the detector tube 3. The battery B is provided for supplying high potential for the plate circuit of the several tubes, a suitable tap 22 being provided for selectively energizing the output circuit of the rectifier tube 3 at different potential than 100

is supplied to the plate circuits of tubes 1 and 2. A suitable responsive device 23 is connected in the output circuit of the rectifier tube 3.

5 It is well known that unstable conditions exist at particular frequencies when the electron tube circuits are tuned. Each of the stages of amplification is subject to self-excitation as a result of which regenerative currents are set up between the input and output circuits of each of the tubes resulting in the production of undesired circulating currents and the generation of undesired oscillations.

15 In order to prevent the instability of the amplification system and the undesired oscillation thereof, I provide means in the electron tube circuits which while not effective when the system is not in oscillation, become effective to prevent oscillation of the amplification system when undesired circulating currents become existent in the amplifier circuits. I insert non-inductive resistors R_1 in each of the grid leads of the radio frequency amplifying circuit as illustrated in Fig. 1. I may insert these resistors as represented at R_3 and R_4 in Fig. 2 of the drawings, in the filament leads of the several tubes in the amplification system. These resistors each act as an absorbing medium when the system becomes unstable and oscillates, but when the system is not in condition of oscillation the resistors are not effective. The reason for this will be readily appreciated when it is observed that the introduction of several hundred ohms of series resistance in the filament grid circuit which is normally many thousand ohms in resistance will not alter the damping characteristics of the circuit with respect to the passage of signaling energy. However, when a condition of oscillation exists, then the oscillating current must traverse the resistance R_1 and R_2 , or R_3 and R_4 and be absorbed thereby.

45 I provide additional means for preventing oscillatory currents in the tube circuits by introducing a non-inductive resistance R_5 in the plate circuit of the detector tube 3 so that oscillatory currents which may be passed through the detector tube 3 are absorbed and prevented from entering the audio frequency circuits of the receiving system. The interposition of resistance R_5 in the output circuit of the detector tube 3 has been found very effective in the elimination of stray oscillations which may pass through the audio frequency amplifying system by the capacity couplings offered by the electrodes of the tube 3. The value of each of the resistors R_1 , R_2 , 50 R_3 , R_4 and R_5 is not critical, but must be initially set when the circuits are adjusted in the receiving apparatus. I provide condensers 24, 25 and 26 which serve as by-pass condensers for radio frequency currents.

65 In Fig. 3 I have shown another method of

accomplishing the desirable results of the elimination of the unstable condition in each stage of a radio frequency amplifier. In this arrangement a bridge method is provided with the resistors disposed in the bridge arms for obtaining a complete balance. In Fig. 3 I have shown an electron tube 2 having its input circuit connected with secondary winding 10 tuned by variable condenser 12. The tube 2 contains a filament or cathode 2^a, a grid or control member 2^b, and a plate or anode 2^c. The inherent intra-electrode capacity existent between the grid electrode 2^b and plate electrode 2^c is represented by condenser G_c . The output or plate circuit of the tube 2 includes the primary winding 14 of transformer 15 to which secondary 16 is coupled. The resistors R_1 and R_2 form two arms of a bridge circuit represented in Fig. 4 where condenser C_c is the compensating capacity arranged to balance the grid capacity G_c which is connected in circuit with the resistor R_2 . I have found that in methods heretofore employed for neutralizing capacity coupling that the employment of inductances and capacity in either arm of the bridge proves ineffective where it is desired to amplify over a wide frequency range. The bridge arrangement of my invention overcomes difficulties experienced in the past for there is no apparent change in the bridge arms of the inductances or variation of distributed capacity for variation of frequency.

70 In the theoretical diagram shown in Fig. 4 I have indicated by like numerals of reference the parts which appear in the circuit diagram of Fig. 3. The non-inductive resistors R_1 and R_2 are shown positioned in the arms of a bridge opposite to the capacities of G_c and C_c .

75 In Fig. 5 I have shown an application of the bridging circuit of Figs. 3 and 4 to a radio frequency amplifier in a radio receiving apparatus. The compensating capacities are shown at C_4 and C_5 , while the capacities 24, 100 80 25 and 26 are the radio frequency by-pass condensers as described in connection with Figs. 1 and 2. The non-inductive resistance R_5 positioned in the plate circuit of the tube 3 operates to absorb undesired oscillatory currents which may pass through the radio frequency amplifier stages and the detector tube 3. In Fig. 5 the tube 1 is illustrated as having the balancing resistors R_1 and R_2 in circuit therewith, while the tube 2 has resistors R_6 , 110 115 R_7 and R_8 in circuit therewith.

85 My invention has proven very practical in its construction and operation, and while I have described certain embodiments of the invention, I desire that it be understood that modifications may be made and that no limitations upon the invention are intended other than those imposed by the scope of the appended claim.

90 What I claim and desire to secure by Let- 130

ters Patent of the United States is as follows:

In a radio frequency amplifying system the combination of a plurality of electron tubes, each having grid, cathode and plate electrodes, an input circuit including the grid and cathode electrodes of each of said tubes, an output circuit including the plate and cathode electrodes of each of said tubes, with the output circuit of one of said tubes inter-linked with the input circuit of a succeeding tube, and a high non-inductive resistance device having one point thereof connected with said cathode electrode and the opposite ends thereof connected one directly with said grid 5 electrode and the other end thereof capacitively connected to said grid electrode through an auxiliary condenser, the plate electrode and the inherent capacity between said grid and plate electrodes for balancing 10 the capacity coupling of said tubes.

In testimony whereof I affix my signature.

SAMUEL COHEN.
